UNITED STATES PATENT OFFICE

RICHARD M. CRAIG, OF SAN ANTONIO, TEXAS, ASSIGNOR TO ANIMATED COLOR ADVERTISING, INC., OF NEW YORK, N. Y., A CORPORATION OF NEVADA

DISPLAY APPARATUS

Original application filed August 14, 1925, Serial No. 50,330. Divided and this application filed January 7, 1929. Serial No. 330,930.

This invention relates to display apparatus and more particularly to an advertising sign of the type disclosed in my Patent No. 1,698,216, issued January 8, 1929, of which 5 the present application constitutes a division.

One object of the invention is to provide a sign which will be novel and attractive in appearance and hold the attention of an observer for a relatively long length of time 10 and thereby serve very effectively as an advertising medium.

Another object of the invention is to provide a sign having an object painted thereon against a background in different 15 positions capable of being assumed by the object and companion lighting means consisting of colored lights emitting spectral rays having such relation to the colors used upon the sign board that as different colored 20 lights are turned on and off the object will appear to change its position.

The invention is illustrated in the accompanying drawing wherein is shown an embodiment of the invention including a sign 25 board and lights together with a circuit for the lights.

In the description which is to follow, reference will be made to pigment colors and by this term are meant colored pigments or 30 the colors in which the images are represented on the display surface. Where reference is made to spectral colors, such reference applies to colors of the spectrum as represented by colored light rays. Reference 35 will also be made to neutral colors, which I employ as backgrounds, and by neutral colors I mean such as do not materially change under the spectral colors by which the images are displayed or, in other 40 words, those which display no decided color characteristics such as relate to primary colors, and remain of about the same apparent density under complementary or primary colored light rays.

45 The drawing illustrates one embodiment of the invention and in this embodiment the display surface is indicated by the numeral 33 and has dark neutral background areas 34 painted thereon and red background areas 35. The representation in this

figure is that of a see-saw or a teeter-totter which, in one position of its movement is illustrated in plain white, as indicated by the numeral 36, the see-saw in this position being represented upon the red background 55 35. In its other position, the see-saw or teeter-totter is represented, as at 37, in red upon the dark neutral backgrounds 34. The stand upon which the see-saw is supported for rocking movement is represented in 60 white, as indicated by the numeral 38, and is located between two of the background areas 34 and 35, it being observed that the areas 34 are diagonally oppositely located and that the areas 35 are likewise diagonally 65 oppositely located. Red light bulbs 39 and blue bulbs 40, or other equivalent sources of spectral colored light are so arranged with relation to the display surface that the same may be flooded with red rays 70 or with blue rays, and it will be understood that when the surface is flooded with red light rays the image 36 will be obliterated but the image 37 will stand out substantially 75 white against the background areas 34. When the surface is flooded with blue light rays, the image 37 will be obliterated and the image 36 will stand out substantially 80 white against the then apparently black background 35. Under both conditions, the support or pedestal 38 will be visible. It will be understood, of course, that in this embodiment of the invention the backgrounds 35 might be green and the image 37 might likewise be green, in which event 85 the image 37 would stand out under the blue light illumination of the display surface and the image 36 would stand out under the red light illumination of the surface.

It is, of course, essential to employ means 90 for effecting illumination of the display surface which means will operate automatically, and inasmuch as there are many flashing devices which may be employed for this purpose, I have illustrated in connection with the figure a flasher indicated as a whole by the reference letter A, which may be a rotary disc of insulating material having concentric series of contact strips B and C upon its face in circuit with a shaft D which 95 100

supports the disc for rotation, wires E serving to electrically connect the said contact strips and the shaft, and a conductor wire F being led from the shaft to one side of a source of current supply indicated by the numeral G. A conductor wire H leads from the other side of the source of current supply and is connected to the sockets for all of the electric light bulbs regardless of their distinctive colors. Brushes I and J are arranged to coat respectively with the contact strips B and C, and conductor wires K and L are led respectively from the brushes I and J and are connected, one with the other terminal of each socket for a light bulb one color and the other with the other terminal of the socket for each light bulb of the other color. The contact strips B and C are arranged in staggered relation so that the circuit will be successively alternately closed through the bulbs of the two distinctive colors.

Having thus described the invention, I claim:

25. Display apparatus comprising a display surface having a background a portion of the area of which is of a dark neutral color and another portion of a distinctive pigment color, the first-mentioned area bearing a representation of matter to be displayed in a distinctive pigment color, the other area bearing similar matter to be displayed and represented in a light neutral color, and means for displaying said surface 30 successively in the presence of contrasting spectral colors one of which corresponds substantially to the first-mentioned representation in a pigment color and the second-mentioned background area color, and the 35 other of which is contrasting to the said background-area distinctive pigment color.

40. In testimony whereof I affix my signature.

RICHARD M. CRAIG. [L. S.]
